UNITED STATES PATENT OFFICE.

CHARLES B. GOLDSMITH, OF EAST HARTFORD, CONNECTICUT.

FEED MECHANISM FOR SAFETY-PIN CARDING MACHINES.

Application filed March 10, 1922. Serial No. 542,618.

To all whom it may concern:

Be it known that I, CHARLES B. GOLDSMITH, a citizen of the United States, and a resident of East Hartford, in the county 5 of Hartford and State of Connecticut, have invented certain new and useful Improvements in Feed Mechanisms for Safety-Pin Carding Machines, which improvements are fully set forth in the following specification.

10 This invention relates to improvements in mechanisms of that class available for receiving in a promiscuous mass, a supply of closed safety-pins; selecting safety-pins singly from said mass; and conducting, accordingly, 15 said selected safety-pins to a point, as the receiving element or member of a suitable carding machine, removed from the mass aforesaid, for delivery thereof, such constructions being well-designated 20 feed mechanisms for safety-pin carding machines.

The object of this invention is to provide a feed mechanism of the character above indicated which shall be simple and inexpensive as regards its construction, durable, 25 efficient and dependable in practical service; convenient in its application to practical purposes; and which shall possess certain well-defined advantages over prior analogous constructions.

The invention consists in the combinations, details and parts to be hereinafter more specifically referred to and set forth in the claims hereto appended, and whereby 35 the attainment of the foregoing object is rendered practicable.

The invention is clearly illustrated in the accompanying drawings, wherein:

Fig. 1 is a plan view of a feed mechanism 40 embodying my said improvements.

Fig. 2 is a side elevation of same.

Fig. 3 is a vertical, transverse section of the mechanism, as along the dotted line 3—3 of Fig. 1.

Fig. 4 is a rear elevation of the construction.

Fig. 5 is a cross-section of one of the feed-chutes made use of, as along the dotted line 5—5 of Fig. 1, scale enlarged.

Fig. 6 is a front elevation of the hopper, including the parts more immediately co-operating therewith, the feed-chute removed.

Fig. 7 is a detail view showing in perspective and detached the intake end-portion of 55 one of the feed-chutes made use of.

Fig. 8 is a detail view showing in perspective a fragment of the feed-chute base, the pin-diverter assembled therewith, and the insert made use of.

Having reference to the accompanying 60 drawings, wherein similar reference-numerals denote like parts throughout the several views, I, in carrying out my present invention, primarily provide a hopper for receiving the closed safety-pins to be duly manipulated and conducted, as to the receiving member of a carding machine, said hopper consisting in part, in this instance, of opposite upstanding side-members 2, 2', here shown as being connected at their rear edges 70 by suitable tie-pieces 3, 3', and further connected at a point suitably in advance of said tie-pieces, by a medial tie-bar 4.

5 is a back-board disposed to reciprocate vertically, as at its opposite side-edges in 75 vertical ways 5', 5'', formed in the side-members 2, 2', at the upper inner faces thereof.

I further interpose between the tie-bar 4 and the back-board, and more essentially the 80 lower edge of the latter, a pin-supporting bottom 6, said bottom being generally tiltable with relation to the tie-bar 4 and co-acting at its rear margin with the back-board 5 to this end.

The foregoing tiltable disposition of the bottom 6 provides for the effectual agitation, in practice, of the mass of pins supported thereby and incidentally the periodical shifting of such pins en masse to the 85 advance or delivery margin of said bottom at each upward throw or travel thereof, and as determined in this instance by each upward throw or travel of the back-board 5, to be hereinafter more fully explained.

While the bottom 6 may be formed from any suitable material, I prefer that material having greater or less flexibility, as wire-mesh, canvas, or the like, be availed of in this connection.

It may be here pointed out, and from the foregoing it will be seen, that my present improved hopper proper is characterized by the provision therein of constituent co-acting parts whereby essential agitation and 100 intermittent shifting en masse of the contents of the hopper are peculiarly and effectually accomplished in the practical operation of my present improved feed mechanism.

100

105

110

7 denotes a main operating shaft, suitably journaled, as in the opposite side-members 2, 2', in advance of the bottom 6, and having firmly mounted thereon, a take-off drum 7', the latter being fitted, circumferentially thereof and suitably spaced apart, with a plurality of take-off studs 8.

The tie-bar 4 is so positioned between the side members 2, 2', that the front margin of the bottom 6, overlying said tie-bar in this instance, lies in feeding contiguity to the drum 7', at the rear side thereof and in parallelism therewith, said tie-bar, including the margin of the bottom 6 overlying the same, being best kerfed at intervals therealong and substantially as shown at 8', to provide due clearance for the studs 8, the drum 7' being rotated.

It is desirable that means be provided for automatically actuating the back-board 5, and hence the bottom 6 for the agitation and shifting of the mass of pins supported thereby, as hereinbefore alluded to; and to the attainment of this end I contemplate employing a crank-shaft 9, fitted with a crank 9' and suitably journaled, as in the side-members 2, 2', below and best in approximately the plane of, the back-board 5, a connecting-rod 10 being operatively conjoined at its upper end with said back-board, as at the point 10', and operatively conjoined at its lower end with the crank 9', and whereby the back-board aforesaid is caused to reciprocate vertically upon the shaft 9 being rotated, as will be readily understood.

It is further desirable that transmission means be provided whereby the crank-shaft 9 shall be caused to rotate at a proper speed-rate relative to the speed-rate of the operating shaft 7; and to the attainment of this end I contemplate the employment of a driving toothed-wheel 11, firmly mounted on the shaft 7, and to receive which said shaft projects through and suitably beyond the side-member 2, said driving toothed-wheel meshing at all times with a suitable intermediate toothed-wheel 12, rotatably mounted on a suitable stub-shaft 13, and said intermediate toothed-wheel in turn meshing at all times with a suitably reduced follower or pinion 14, firmly mounted on the crank-shaft 9, and to receive which in line with the toothed-wheel 12, said crank-shaft projects through and suitably beyond the side-member 2, all as clearly illustrated in Fig. 1 of the drawings.

It will be seen that with the parts assembled as above defined, turning of the operating shaft 7, as in the direction indicated by the arrow 15, (Fig. 2), will result in the turning of the crank-shaft 9 and at a speed-rate proper with relation thereto; and the turning of the shaft 7 may be effected in any appropriate manner, though prefer-

ably, and particularly where the mechanism is to be power-operated, through the medium of a suitable pulley 16, fast on the operating shaft and in belt connection, through the medium of a suitable belt 17, with any available and appropriate source of power and motion, said operating shaft projecting through and suitably beyond the side member 2', to receive said pulley.

A feed-chute leads from a point relatively below the take-off drum 7' and at a suitable inclination downwardly and forwardly therefrom, said feed-chute comprising essentially a base 18 in conjunction with which, at the receiving end-portion thereof, are arranged opposite upstanding guards 19, 19', said guards being cut away to conform to the adjacent side of the drum 7' and hence stand in close proximity thereto.

A bridge-plate 20 is arranged with an inclination downwardly and rearwardly between the guards 19, 19'; and to reversely underlie which is positioned an initial impetus plate 21, having a suitable curvature upwardly at its receiving portion, the leading-off end-portion thereof bearing on the base 18, all as clearly shown in Fig. 3 of the drawings.

It is desirable that the pins which shall slide end-on downwardly along the base 18 shall do so along a course of movement restricted to one, and preferably the far, side margin thereof; and while the attainment of this end may be accomplished in various ways, I contemplate the employment of a base 18 whose top surface, for the purpose aforesaid, shall incline transversely and downwardly from one side edge to the opposite side edge thereof, as clearly indicated in the drawings.

In any event it is essential that there be employed at and along the depressed side edge of the base, an upstanding abutment wall, as 22, along and in contact with which the pins undergoing treatment also slide.

The base 18 is provided with a main overflow opening 23, the general form and purpose of which will be more specifically referred to hereinafter.

There is fastened to the base 18, in any convenient manner and as at the point 24, a super-pin diverter, whose medial portion or body 25 extends rearwardly along the far edge of the opening 23, measurably overlies said opening, and is merged at its free or rear end into an angularly turned terminal 26 which in turn overlies, suitably elevated thereabove, the course of movement of the pins being treated.

It will be seen, therefore, that due clearance is provided between the terminal 26 and that section of the base 18 thereunder for the free passage of the normally moving pins underneath said terminal, and for further movement downwardly along the said

feed-chute. But, should any of the pins being treated ride, previously to reaching the terminal 26, upwardly and upon the pin next in advance thereof, such super-pin will 5 engage end-on the terminal aforesigned and be thereby diverted to and for movement by its own gravity downward through the main opening 23 and into any suitable receptacle placed thereunder, the super-pins thus collected being returned by and at the convenience of the operator to the interior of the hopper of the mechanism.

To facilitate the foregoing deflection or divergence of the super-pins the terminal 15 aforesigned is best fitted with a pin-diverting face 27, which is engaged end-on by the oncoming super-pins, as will be readily understood.

Should the pins leaving the lower termi- 20 minus of the feed-chute be not there taken care of at any time with proper despatch, it can well happen that the downwardly moving pins may line back, each end-on against the pin next in advance thereof, and to a 25 predetermined point upwardly along the feed-chute, such point being conveniently located adjacent the body 25 of the super-pin diverter aforesigned, and whereat is also located a minor overflow opening or clear- 30 ance, 28, which lies relatively in line with the diverter body aforesigned, at the far side thereof, and constitutes in this instance a minor lateral extension of the opening 23, at its far edge.

35 In this connection, each of the oncoming pins which shall reach a position adjacent to or in due registry with the minor opening aforesigned, (said opening being properly positioned to this end relatively to the upper terminus of the line of lined-up pins), will be deflected by the unbroken or compact line of pins in advance thereof, laterally from its course of movement and for passage by its own gravity downwardly 40 through the opening 28 and into any suitable receptacle placed thereunder, which action on the part of such diverted pin is materially facilitated by under-cutting the body 25 at its far side and substantially as 45 shown at 25', Fig. 8.

50 It is preferred that the inclination of the feed-chute made use of be such that the pins which may be deposited therein may not slide downwardly therealong save under a vibratory effect imparted to the chute; and while devices of varying types may be availed of to this end, I purpose making use 55 of a vibratory hammer 29 which is attached through the medium of its flexible shank 30 to, say, the base 18 at the under side thereof.

31 is a minor shaft freely rotating in suitable hangers 31' depending opposedly from the base 18, and having firmly mounted thereon a toothed hammer-actuating wheel 60 32, the teeth whereof consecutively engage

and release, say, the tongue 33 with which the hammer aforesigned is provided, and said minor shaft being duly rotated.

Rotation of the minor shaft 31 may be conveniently effected through the medium of 70 a driven sheave 34, fast thereon, and in belt connection, through the medium of a suitable belt 35, with a suitable driving medium, as the enlarged drive-sheave 36 fast on the main operating shaft 7.

75 Normally the hammer 29 lies in contact with the under face of the base 18 and under a more or less yielding stress afforded by its flexible shank 30, the teeth of the wheel 32 consecutively co-acting with the tongue 80 of said hammer in a manner to consecutively retract and release the same; and said hammer when thus repeatedly released being permitted to snap back into contact with the base aforesigned and deliver thereto, accordingly, a tap or blow adapted to vibrate the same, and sufficiently so to cause any safety pins which would otherwise remain at rest on the base 18 to slide downwardly 85 therealong at a proper rate of speed.

90 In the practical operation of my improved feed mechanism the safety-pins to be treated are introduced in a promiscuous mass into the interior of the hopper of the mechanism, such mass of pins being then essentially supported by the tiltable bottom 6 thereof.

95 Now, power and motion having been imparted to the take-off drum 7', as through the medium of its supporting shaft and the 100 driving parts co-acting therewith, the mass of pins, under the tilting action of the bottom 6, is not only agitated in a manner to keep the pins comprised therein essentially 105 distangled and each essentially free to be selected from the mass, but to ensure, at each upward throw of the bottom 6, the shifting of said pins en masse to and into feeding relation with the take-off drum 7', 110 as hereinbefore explained,—the tilting action of the bottom aforesigned being automatically effected, in this instance, through the medium of the crank-shaft 9, rotating, in this instance, under power and motion derived from the operating shaft 7, through 115 the medium of suitable transmission elements, such as hereinbefore referred to, and further through the medium in this instance of the vertically reciprocating back-board 5 and connecting-rod 10 interposed between 120 the same and the crank afforded by said crank-shaft, the bottom aforesigned co-acting at its rear margin with said back-board and being movable upwardly and downwardly in unison therewith, as will be readily 125 understood.

130 As the drum 7' continues to rotate (essentially in the direction indicated by the arrow 15, Fig. 2), each of the studs 8 thereof engages and takes with it some one of the

pins comprised in the mass thereof, now in feeding relation to the drum 7', carries it upwardly and well over said drum, and then releases it; whereupon such released pin 5 drops by its own gravity onto the bridge-plate 20, downwardly along which it then slides and from the lower end of which it escapes and again falls to and upon the impetus-plate 21, downwardly along which 10 it in turn slides to and assumes an end-on position upon the base 18.

Now, a vibratory effect being imparted to the base 18, as hereinbefore explained or otherwise, such pins as may now be deposited thereon will advance by a sliding motion endwise downwardly therealong, and properly in rotation one after another; and so long as each thereof shall continue to move thus separately, the same will pass 15 under the raised terminal of the diverter aforesaid and from thence continue its course onward downwardly along the chute to the delivery end thereof, there being no congestion of pins therein.

25 On the other hand, should any pin, by any chance, mount the pin next in advance thereof and previously to reaching the diverter terminal, such super-pin will be diverted by said terminal laterally to and for 30 a falling movement through the general overflow opening 23, as hereinbefore explained, and the pin so mounted by such super-pin being then free to continue separately its course of movement downwardly 35 along said chute; but if the pin so moving should encounter, after passing the diverter terminal, the pin next in advance thereof and constituting the rear pin in a line of pins arrested in advance thereof, such moving pin, and other separately oncoming pins, will be diverted by such rear, arrested pin laterally to and for a falling movement 40 through the minor overflow clearance 28, as hereinbefore explained, and thereby obviating the temporary stopping of the operation of the operating parts of the mechanism,—it being understood that the minor clearance 28 shall be properly located relatively to the rear end of the compact line 45 of pins which may form within the chute from such clearance downwardly to the delivery end of the chute.

The operation of my improved mechanism should be apparent from the foregoing description thereof, including the parts availed of for imparting a vibratory effect to the feed-chute made use of; and it will be understood that the pins deliverable from the feed-chute at the delivery end 50 thereof may be taken care of in any appropriate manner, it being intended that the same shall be delivered to the receiving member of a suitable carding machine to be duly carded thereby, and whereby is rendered essential the employment, as clearly 55

indicated in the accompanying drawings, of a plurality of feed-chutes similar to 18, arranged side-by-side, and corresponding in number to the number of pins it is desired shall constitute a row thereof when 70 duly mounted on a card provided to receive the same.

It will be further seen that my improved mechanism is well adapted for the purposes for which it is intended, being markedly 75 simple in its construction, positive in operation and whose parts are readily accessible, and further that the same may be modified to a considerable extent, particularly as regards the means availed for agitating the mass of pins contained at any time within the hopper, the specific means availed of for imparting a vibratory effect to the base 18, and various minor details of the general construction without material 80 departure being made from the spirit and principle of my invention as set forth in and coming within the scope of the claims here-to appended.

It is here pointed out that to facilitate the 90 formation of the general and minor overflow openings aforesaid, for the base 18, I contemplate the employment of a relatively narrow insert 37, which is snugly inserted into said base from the far margin 95 thereof, said insert appearing clearly in Fig. 8 of the drawings.

Having thus described my invention, I claim:

1. A hopper for a mechanism of the class 100 herein described comprising suitable side-members and a flexible, pin-supporting bottom whose advance margin constitutes a delivery margin therefor, and means adapted to carry the rear margin thereof 105 upwardly and downwardly in relation to said delivery margin.

2. A hopper for a mechanism of the class 110 herein described comprising suitable side-members and a pin-supporting bottom whose advance margin constitutes a delivery margin therefor; a movable back-board co-acting 115 with the bottom aforesaid and arranged to carry, accordingly, the rear margin of said bottom upwardly and downwardly in relation to the delivery margin thereof; and means for actuating said back-board.

3. A hopper for a mechanism of the class 120 herein described comprising suitable side-members and a pin-supporting bottom whose advance margin constitutes a delivery margin therefor; a vertically reciprocating back-board co-acting with the bottom aforesaid and arranged to carry, accordingly, the rear margin of said bottom upwardly and downwardly in relation to the delivery margin thereof; and means for actuating 125 said back-board, said means including a rotatable crank-shaft, means for rotating 130

feed-chute. But, should any of the pins being treated ride, previously to reaching the terminal 26, upwardly and upon the pin next in advance thereof, such super-pin will 5 engage end-on the terminal aforesaid and be thereby diverted to and for movement by its own gravity downward through the main opening 23 and into any suitable receptacle placed thereunder, the super-pins thus collected being returned by and at the convenience of the operator to the interior of the hopper of the mechanism.

To facilitate the foregoing deflection or divergence of the super-pins the terminal 15 aforesaid is best fitted with a pin-diverting face 27, which is engaged end-on by the oncoming super-pins, as will be readily understood.

Should the pins leaving the lower terminus of the feed-chute be not there taken care of at any time with proper despatch, it can well happen that the downwardly moving pins may line back, each end-on against the pin next in advance thereof, and to a 25 predetermined point upwardly along the feed-chute, such point being conveniently located adjacent the body 25 of the super-pin diverter aforesaid, and whereat is also located a minor overflow opening or clearance, 30 28, which lies relatively in line with the diverter body aforesaid, at the far side thereof, and constitutes in this instance a minor lateral extension of the opening 23, at its far edge.

35 In this connection, each of the oncoming pins which shall reach a position adjacent to or in due registry with the minor opening aforesaid, (said opening being properly positioned to this end relatively to the upper terminus of the line of lined-up pins), will be deflected by the unbroken or compact line of pins in advance thereof, laterally from its course of movement and for passage by its own gravity downwardly 40 through the opening 28 and into any suitable receptacle placed thereunder, which action on the part of such diverted pin is materially facilitated by under-cutting the body 25 at its far side and substantially as 45 shown at 25', Fig. 8.

50 It is preferred that the inclination of the feed-chute made use of be such that the pins which may be deposited therein may not slide downwardly therealong save under a vibratory effect imparted to the chute; and while devices of varying types may be availed of to this end, I purpose making use 55 of a vibratory hammer 29 which is attached through the medium of its flexible shank 30 to, say, the base 18 at the under side thereof.

31 is a minor shaft freely rotating in suitable hangers 31' depending opposedly from the base 18, and having firmly mounted thereon a toothed hammer-actuating wheel 60 32, the teeth whereof consecutively engage

and release, say, the tongue 33 with which the hammer aforesaid is provided, and said minor shaft being duly rotated.

Rotation of the minor shaft 31 may be conveniently effected through the medium of 70 a driven sheave 34, fast thereon, and in belt connection, through the medium of a suitable belt 35, with a suitable driving medium, as the enlarged drive-sheave 36 fast on the main operating shaft 7.

75 Normally the hammer 29 lies in contact with the under face of the base 18 and under a more or less yielding stress afforded by its flexible shank 30, the teeth of the wheel 32 consecutively co-acting with the tongue 80 of said hammer in a manner to consecutively retract and release the same; and said hammer when thus repeatedly released being permitted to snap back into contact with the base aforesaid and deliver thereto, accordingly, a tap or blow adapted to vibrate the same, and sufficiently so to cause any safety pins which would otherwise remain at rest on the base 18 to slide downwardly 85 therealong at a proper rate of speed.

90 In the practical operation of my improved feed mechanism the safety-pins to be treated are introduced in a promiscuous mass into the interior of the hopper of the mechanism, such mass of pins being then essentially supported by the tiltable bottom 6 thereof.

95 Now, power and motion having been imparted to the take-off drum 7', as through the medium of its supporting shaft and the 100 driving parts co-acting therewith, the mass of pins, under the tilting action of the bottom 6, is not only agitated in a manner to keep the pins comprised therein essentially distangled and each essentially free to be 105 selected from the mass, but to ensure, at each upward throw of the bottom 6, the shifting of said pins en masse to and into feeding relation with the take-off drum 7', as hereinbefore explained.—the tilting action 110 of the bottom aforesaid being automatically effected, in this instance, through the medium of the crank-shaft 9, rotating, in this instance, under power and motion derived from the operating shaft 7, through 115 the medium of suitable transmission elements, such as hereinbefore referred to, and further through the medium in this instance of the vertically reciprocating back-board 5 and connecting-rod 10 interposed between 120 the same and the crank afforded by said crank-shaft, the bottom aforesaid co-acting at its rear margin with said back-board and being movable upwardly and downwardly in unison therewith, as will be readily understood.

125 As the drum 7' continues to rotate (essentially in the direction indicated by the arrow 15, Fig. 2), each of the studs 8 thereof engages and takes with it some one of the 130

pins comprised in the mass thereof, now in feeding relation to the drum 7', carries it upwardly and well over said drum, and then releases it; whereupon such released pin 5 drops by its own gravity onto the bridge-plate 20, downwardly along which it then slides and from the lower end of which it escapes and again falls to and upon the impetus-plate 21, downwardly along which 10 it in turn slides to and assumes an end-on position upon the base 18.

Now, a vibratory effect being imparted to the base 18, as hereinbefore explained or otherwise, such pins as may now be deposited thereon will advance by a sliding motion endwise downwardly therealong, and properly in rotation one after another; and so long as each thereof shall continue to move thus separately, the same will pass 20 under the raised terminal of the diverter aforesaid and from thence continue its course onward downwardly along the chute to the delivery end thereof, there being no congestion of pins therein.

25 On the other hand, should any pin, by any chance, mount the pin next in advance thereof and previously to reaching the diverter terminal, such super-pin will be diverted by said terminal laterally to and for 30 a falling movement through the general overflow opening 23, as hereinbefore explained, and the pin so mounted by such super-pin being then free to continue separately its course of movement downwardly 35 along said chute; but if the pin so moving should encounter, after passing the diverter terminal, the pin next in advance thereof and constituting the rear pin in a line of pins arrested in advance thereof, such moving pin, and other separately oncoming pins, will be diverted by such rear, arrested pin laterally to and for a falling movement 40 through the minor overflow clearance 28, as hereinbefore explained, and thereby obviating the temporary stopping of the operation of the operating parts of the mechanism,—it being understood that the minor clearance 28 shall be properly located relatively to the rear end of the compact line 45 of pins which may form within the chute from such clearance downwardly to the delivery end of the chute.

50 The operation of my improved mechanism should be apparent from the foregoing description thereof, including the parts availed of for imparting a vibratory effect to the feed-chute made use of; and it will be understood that the pins deliverable from the feed-chute at the delivery end thereof may be taken care of in any appropriate manner, it being intended that the same shall be delivered to the receiving member of a suitable carding machine to be 55 duly carded thereby, and whereby is rendered essential the employment, as clearly

indicated in the accompanying drawings, of a plurality of feed-chutes similar to 18, arranged side-by-side, and corresponding in number to the number of pins it is desired shall constitute a row thereof when 70 duly mounted on a card provided to receive the same.

It will be further seen that my improved mechanism is well adapted for the purposes for which it is intended, being markedly 75 simple in its construction, positive in operation and whose parts are readily accessible, and further that the same may be modified to a considerable extent, particularly 80 as regards the means availed for agitating the mass of pins contained at any time within the hopper, the specific means availed of for imparting a vibratory effect to the base 18, and various minor details of the general construction without material 85 departure being made from the spirit and principle of my invention as set forth in and coming within the scope of the claims here-to appended.

It is here pointed out that to facilitate the 90 formation of the general and minor overflow openings aforesaid, for the base 18, I contemplate the employment of a relatively narrow insert 37, which is snugly 95 inserted into said base from the far margin thereof, said insert appearing clearly in Fig. 8 of the drawings.

Having thus described my invention, I claim:

1. A hopper for a mechanism of the class 100 herein described comprising suitable side-members and a flexible, pin-supporting bottom whose advance margin constitutes a delivery margin therefor, and means adapted to carry the rear margin thereof 105 upwardly and downwardly in relation to said delivery margin.

2. A hopper for a mechanism of the class 110 herein described comprising suitable side-members and a pin-supporting bottom whose advance margin constitutes a delivery margin therefor; a movable back-board co-acting 115 with the bottom aforesaid and arranged to carry, accordingly, the rear margin of said bottom upwardly and downwardly in relation to the delivery margin thereof; and means for actuating said back-board.

3. A hopper for a mechanism of the class 120 herein described comprising suitable side-members and a pin-supporting bottom whose advance margin constitutes a delivery margin therefor; a vertically reciprocating back-board co-acting with the bottom aforesaid and arranged to carry, accordingly, the rear margin of said bottom upwardly and downwardly in relation to the delivery margin thereof; and means for actuating said back-board, said means including a 125 rotatable crank-shaft, means for rotating 130

the same, and a connecting-rod, the latter interposed between the crank of said crank-shaft and said back-board.

4. A feed-chute for a mechanism of the class herein described comprising a base having a suitable transverse inclination and fitted at a point suitably therealong with a general overflow opening, and having associated therewith at its far or depressed 10 edge an abutment wall or flange.

5. A feed-chute for a mechanism of the class herein described comprising a base fitted at a point suitably therealong with a general overflow opening, and supporting 15 a pin diverter, a portion of said diverter being duly elevated relatively to said base, and whereby super-pins traversing said chute are diverted to and for passage through said general opening.

20 6. A feed-chute for a mechanism of the class herein described comprising a base fitted with a general overflow opening and supporting a pin diverter, said diverter partially overlying said opening and affording 25 a terminal which overlies the course of movement of pins along said base and being duly elevated with respect to the latter, said terminal fitted, in turn, with a pin-diverting face whereby super-pins traversing said 30 chute are diverted to and for passage downwardly through said general opening.

7. A feed-chute for a mechanism of the class herein described comprising a base fitted with a general overflow opening and 35 thereat with a minor overflow opening, and a suitable insert, the latter let snugly into

the base at one margin thereof and defining in part at its inner edge said general and minor openings.

8. In a mechanism of the class herein described, in combination, a duly inclined feed-chute including a base; means for feeding safety-pins one-by-one therein; a hammer held to contact under an elastic stress with said base at the underside thereof; and 40 means for intermittently retracting said hammer and releasing the same for a return snap action into contact with said base.

9. In a mechanism of the class herein described, in combination, a duly inclined feed-chute including a base flanged along its far edge; means for feeding safety-pins one-by-one therein; a hammer held to contact under an elastic stress with said base at the 45 under face thereof; and means for intermittently retracting said hammer and releasing the same for a return snap action into contact with said base, said means, last mentioned, embodying a rotatable, toothed-wheel and parts co-acting therewith whereby the same may be rotated.

10. A feed-chute for a mechanism of the class herein described, comprising a base and a suitable abutment-wall or flange, the latter assembled with the base at and suitably along its far edge, said base being fitted, at a suitable point therealong, with a relatively narrow insert whose inner general edge serves to define in part a general overflow opening and a minor overflow opening for 70 said chute.

CHARLES B. GOLDSMITH.
